UNITED STATES PATENT OFFICE.

WILLIAM G. FLUHARTY, OF ROCKVILLE CENTER, NEW YORK.

DESIGN FOR A TAPE-TRANSMITTER CASING.

59,956.

Specification for Design.

Patented Dec. 13, 1921.

Application filed July 23, 1921. Serial No. 487,202. Term of patent 3½ years.

To all whom it may concern:

Be it known that I, WILLIAM G. FLUHARTY, a citizen of the United States, and a resident of Rockville Center, in the county of Nassau and State of New York, have invented a new, original, and ornamental Design for a Tape-Transmitter Casing, of which the following is a specification, reference being had to the accompanying drawing, forming part thereof.

Figures 1 and 2 are perspective views of a tape transmitter casing, showing my new design.

I claim:

The ornamental design for a tape transmitter casing, as shown.

W. G. FLUHARTY.
